UNITED STATES PATENT OFFICE.

JOHN J. HOEY, OF PROVIDENCE, RHODE ISLAND.

TENTERING-MACHINE.

1,098,152.

Specification of Letters Patent.

Patented May 26, 1914.

Application filed June 23, 1911. Serial No. 634,912.

To all whom it may concern:

Be it known that I, JOHN J. HOEY, a citizen of the United States, residing at Providence, in the county of Providence and State of Rhode Island, have invented certain new and useful Improvements in Tentering-Machines, of which the following is a specification.

My invention relates to tentering-machines for use in finishing textile materials and consists particularly of improvements in the mechanism for reciprocating the side-rails or frames on which the conveyer or cloth-clamp chains are carried.

The object of my improvement is to secure a more uniform movement of the side-rails and to relieve the strain and stress on the driving mechanism due to momentum and inertia of the moving parts.

The invention is fully described in the following specification, illustrated by the accompanying drawings, in which:—

Figure 1 is a side elevation of the driving end of a tentering-machine showing my improved rail-reciprocating mechanism applied thereto; Fig. 2, a plan view of the same with the side-rails indicated by dash-lines, so as not to obscure the view of the driving devices arranged underneath; Fig. 3, an end view showing one of the cross-arms for the side-rails mounted on its supporting standard; Figs. 4 and 5, detail views of the clutch and brake devices for the reciprocating mechanism; Fig. 6, a detail view of one of the crank-disks for reciprocating the side-rails.

Referring to Figs. 1 and 2, I have here illustrated a tentering-machine arranged with the side-rails A and B carrying sprocket-wheels b at their ends, the latter adapted to drive the endless conveyer-chains made up of cloth-clamps, not here shown in detail. The rails A and B are supported on cross-arms C, D, etc. arranged at intervals along the machine and swiveled on standards E, F, etc., see Fig. 3. The cross-arms C, D are preferably pivoted on bearings c on the standards E, F and have rolls d adapted to run on the tracks e, f to carry the weight of the rails. The rails A and B are mounted on pivot-blocks a' and b', see Fig. 3, which allow the arms C and D to oscillate about their axes to reciprocate the rails. Preferably these blocks are adjustable along the cross-arms by means of the screw-threaded rods b², gen-

erally arranged to be rotated through gears b⁴ connecting them with the longitudinal shaft b³ which carries a hand-wheel b⁵ at one end, see Fig. 2. By this means the rails 60 can be adjusted toward and away from each other to adapt the chains to different widths of cloth.

Supported in bearings g, g mounted on the bed G of the machine is a main drive-shaft H carrying a belt-pulley h or other driving element at one end. The shaft H also carries a pulley or chain-wheel h' connected to a wheel j on the horizontal shaft J by a belt or chain i. The shaft J carries worms k at both ends which mesh with worm-gears k' mounted on stud-shafts K, see Fig. 1. The stud-shafts K are connected by universal joints l to telescopic shafts L which, in turn, are connected by similar joints l' to the stud-shafts M mounted in bearings on the rails A and B and carrying the sprocket-wheels b. This arrangement of driving mechanism for the sprocket-wheels is described in detail in my Patent No. 80 974,271, dated November 1, 1910, and provides for transmitting rotation from a fixed shaft to the constantly shifting sprocket-wheel shafts without backlash or lost motion.

The sprocket-wheels, as before explained, serve to continuously drive the conveyer-chains which carry cloth-clamps for gripping the edges of the fabric and feeding it through the machine. During the travel of 90 the cloth from one end of the machine to the other the side-rails are operated to pull and stretch the fabric in a well known manner now generally used for giving the finish to certain kinds of material. This action is 95 effected by reciprocating the rails longitudinally in opposite directions during the operation of the machine. To accomplish this, I provide the novel arrangement of mechanism now described: Extending across the 100 bed of the machine parallel with the drive-shaft H is a horizontal shaft N mounted in the bearings n, n. The shaft N is rotated from the drive-shaft H by means of a belt or chain n' connecting the pulley or chain-wheel h² with the wheel O. The wheel O is 105 preferably arranged free to rotate on the shaft N but is connected therewith to drive the shaft by means of a clutch-device shown in detail in Fig. 4. This consists essentially 110 of a clutch-member P free to slide on the shaft N, but rotatably secured thereto by

suitable means, such, for instance, as the spline p , and formed with a cone face p' adapted to engage the corresponding interior face o of the wheel O . A coiled spring q , held between the end of the member P and a collar q' secured to the shaft N , serves to normally retain the clutch in engagement with the wheel O . The clutch P is adapted to be disengaged from the wheel O by means of a hand lever R pivoted at r on the bed of the machine. Secured to the lever R is a ring or hoop r' carrying a pin r^2 which, in conjunction with a pin r^3 projecting from the lever itself, engages a groove p^2 on the periphery of the clutch P . When the lever R is swung in the direction indicated by the arrow, Fig. 4, the pins r^2 and r^3 act on the side of the groove p^2 to slide the clutch P out of engagement with the wheel O and the lever is maintained in this position by means of a usual arrangement of pawl r^4 engaging the teeth on the quadrant r^5 and operated by the finger-lever r^6 . The lever R is also arranged to actuate a brake-device simultaneously with the disengaging of the clutch-mechanism to arrest the rotation of the shaft N and lock it against further rotation. The brake-mechanism comprises a member S , held fast on the shaft N by means of splines s , s and a set-screw s' , and adapted to take the end thrust of the wheel O , the latter being held between said member and the collar s^2 . The member S is formed with an interior, tapered face s^4 adapted to be engaged by the correspondingly tapered face t of the brake element T . The element T is operated by an arm U pivoted at u on the bed of the machine and having a loop u' extending around the opposite side of the member T , see Fig. 2. Trunnions t' , projecting from the sides of the member T connect it with the arm U and its loop u' and prevent the member T from turning. The arm U is connected to the lever R by a link u^2 and when the lever is moved to slide the clutch P out of engagement with the wheel O the member T is coördinately moved into engagement with the member S to provide a frictional engagement which arrests the rotation of the shaft N and locks it against further turning until the brake is released.

The shaft N carries two worms v , v' arranged in the openings n^2 between the ends of the bearings n , n , see Fig. 2. The worms v , v' mesh with worm-gears v^2 , v^3 mounted on the vertical shafts V and V' . The hubs of the worms v , v' rotate in bearings v^4 formed on or attached to the bed G and suitable casings v^5 inclose both the worms and worm-gears to protect them from dirt and provide oil-tight housings. The arrangement of the shaft N , worms v , v' and gears v^2 , v^3 is similar to the gearing arrangement at the end of the machine which is

used to drive the flexible shafts for the sprocket-wheels, and the whole gives a particularly neat and compact appearance while providing oil-flushed bearings for the operating parts. The shafts V and V' extend upward through bearings x , x on the side frames or standards X , X and carry crank-disks W and W' at their upper ends. The crank-disks W and W' are provided with wrist-pins w , w which are preferably adjustable in relation to the axes of the disks to vary the throw of the cranks. As shown in Figs. 1 and 6, the disks are provided with diametrically extending T-slots w^2 to which are fitted sliding blocks w^3 carrying the wrist-pins w . Each pin w is formed as a stud screwed into the block w^3 with its shoulder w^5 set up against the top face of the latter. There is a slight clearance between the top of the block w^3 and the top of the crank-disk W and a bushing w^6 surrounding the pin w is formed with a flange w^7 adapted to bear on the face of the disk. A washer w^8 bears against the upper end of the bushing w^6 with a clearance between its under side and the shoulder w^9 on the pin w . A nut w^{10} is secured on to the threaded end w^{11} of the pin w and serves to force the bushing w^6 against the face of the crank-disk to bind the block w^3 in the T-slot w^2 . Through this means the block w^3 is retained in position after being adjusted on the crank-disk and I have also found it desirable to provide means for setting both the blocks accurately in relation to the axes of the disks. To this end the disks W and W' are provided with holes w^{12} , etc. adapted to receive the ends of dowel-pins or studs w^{13} screwed through the blocks w^3 . These holes are spaced equidistantly away from the axis of both crank-disks and when the blocks are adjusted with the dowels registering with corresponding holes the wrist-pins on the two disks will be set to have exactly the same throw.

Surrounding the bushing w^6 on the wrist-pin w is a second bushing w^{14} held between the washer w^8 and the flange w^7 . This bushing has a flange w^{15} at its upper end between which and the flange w^7 is pivotally mounted the end of a connecting-rod Y . The opposite end of the rod Y , see Figs. 1 and 2, is connected by a pin y to the eye-bolt y' which extends through one end of the cross-arm D and is secured thereto by the nuts y^2 . By reference to Fig. 1 it will be noted that the shaft N is arranged equidistantly between the two cross-arms C and D and the worm-gears v^2 and v^3 with their vertical shafts V and V' are set on opposite sides of the shaft N . As before stated, the crank-disk W is connected to the cross-arm D by the pitman or connecting-rod Y and a second pitman Y' of equal length connects the disk W' with the cross-arm C in a simi-

lar manner. The worm v and v' are left- and right-handed respectively and as the drive-shaft H is turned in the direction indicated by the arrow 2, Fig. 1, and the shaft 5 N rotated thereby in the same direction, the two vertical shafts V and V' will be turned both in the same direction as indicated by the arrows 3, 3, Fig. 2. The wrist-pins w and w' are set on opposite centers and it will 10 be seen that when the crank-disks are rotated as described the pitmen Y and Y' will be operated in unison to alternately pull and push on the ends of the cross-arms C and D to oscillate the latter about their pivots on 15 the standards E and F. This causes the two side-rails A and B which are pivotally secured to the cross-arms by the blocks a', b' to be reciprocated in opposite directions and the cloth is tentered in the usual well known 20 manner as it feeds through the machine, carried by the endless conveyer chains of clamps. In some cases the fabric is fed through the machine without pulling or stretching it through the reciprocating ac- 25 tion of the side-rails; and when it is so desired to allow the rails to remain at rest it is only necessary to shift the lever R and throw out the clutch P. At the same opera- 30 tion the brake element T is thrown into en- gagement with the member S to lock the shaft N and prevent movement of the side- rails.

An essential feature of improvement in my invention is the arrangement of the 35 crank-disks to operate in horizontal planes with their pitmen connected to opposite ends of the two cross-arms C and D. Through this arrangement the pitmen are adapted to operate in a plane parallel to the 40 line of movement of the side-rails. This gives a direct, straight-line action which prevents cramping, lost motion, or back-lash and also obviates the use of knuckle joints for connecting the driving and driven ele- 45 ments. Heretofore where motion has been transmitted to the side-rails from vertically arranged cranks or similar devices it has been necessary to employ intermediary ele- 50 ments such as long arms or, in some cases, bell-crank levers to convert the rotary motion to a reciprocatory movement and the use of such connections involves numerous extra bearings and couplings which are sub- 55 ject to great strain and consequent wear. With the present arrangement I secure the 60 most direct line of transmission from the cranks to the side-rails, and furthermore, since the pitmen operate in a plane parallel with the line of movement of the rails, there 65 is no tendency to pull down on the ends of the cross-arms and therefore cramping or binding of the arms on their bearings is pre- vented and extra stress avoided. Where vertical arms pivoted below the rails have

ward action of the connecting-rods on the side-rails causes vibration and pounding, resulting in excessive wear on the parts and lost power in operating the machine.

The arrangement of the two crank-disks 70 with their pitmen connected to opposite ends of the two separate cross-arms is a most important feature of the invention. By this means the variation in angular movement of the cranks is compensated for or balanced 75 so that their points of connection with the rails move absolutely in consonance. In other words, the arcal movement of the point of connection of the pitman Y with the arm D corresponds to the arcal move- 80 ment of the point of connection of the pit- man Y' on the arm C and these points have the same ratio of movement with their re- spective cranks. There is, therefore, no lost motion or cramping tendency as would be 85 the case if both cranks were connected to opposite ends of the same cross-arm. The cranks act through their pitmen with both pitmen alternately pulling or pushing on both rails at the same time and a smooth 90 even motion is secured without vibration or pounding and with a minimum of strain on the operating parts.

My new arrangement for transmitting motion from the drive-shaft to the driven 95 shaft and thence to the cranks without the use of bevel or spur gears is also novel as applied to a tentering machine and possesses 100 important features of improvement. The side-rails and conveyer chains carried there- on are of great weight, particularly in large machines which are sometimes nearly one hundred feet long. The movement of such heavy elements is obviously subject to a 105 considerable effect from inertia and momen- tum and these forces tend to cause vibration and jar. Where bevel or spur gears are used to drive the mechanism the clearance be- 110 tween the teeth will allow considerable play and backlash, especially after the gears be- come worn. This results in uneven motion, lost power and great wear on the parts which soon deteriorate to such an extent as to require extensive replacement. In my 115 present arrangement by the use of link-belts or chains and worm-gearing I am enabled to eliminate this vibration due to backlash and by providing a smooth even drive I ren- der the parts less liable to damage and wear and consequently more efficient and durable. 120

Various modifications might be made in the structure and arrangement of the parts without departing from the spirit or scope of the invention; therefore without limiting myself to the exact form shown and de- 125 scribed, what I claim is:—

1. In a tentering-machine, the combina- 130 tion with longitudinally reciprocating side- rails, of means to reciprocate said rails comprising vertical shafts, means to rotate the

- shafts, crank-disks on said shafts, and pitmen extending in opposite directions from the axes of said crank-disks and connected to reciprocate the side-rails with movement in opposite directions.
2. In a tentering-machine, the combination with longitudinally reciprocating side-rails, of means to reciprocate said rails comprising a pair of vertical shafts, means to 10 rotate said shafts, horizontally arranged crank-disks on the shafts, wrist-pins carried by said crank-disks, and pitmen extending in opposite directions from the axes of said crank-disks and connecting the wrist-pins 15 to reciprocate the side-rails.
3. In a tentering-machine, the combination with longitudinally reciprocating side-rails, of means to reciprocate said rails comprising horizontally arranged cranks, means 20 to rotate the cranks, and pitmen extending from the cranks in opposite directions with each pitman connected to reciprocate one of the side-rails.
4. In a tentering-machine, the combination 25 with the side-rails, of means to reciprocate the rails comprising a pair of vertical shafts, worm-gearing arranged to drive both shafts in the same direction, cranks mounted on said shafts and pitmen connecting said 30 cranks to reciprocate the side-rails, said pitmen extending in opposite directions from the axes of the crank-shafts and arranged to operate in a horizontal plane.
5. In a tentering-machine, the combination 35 with a plurality of oscillating cross-arms, of side-rails mounted on said cross-arms, two horizontally arranged cranks, means to rotate the cranks, a pitman connecting one of the cranks to the end of one 40 of the cross-arms, and a second pitman ex-
- tending in the opposite direction and connecting the other crank to the opposite end of the next cross-arm.
6. In a tentering-machine, the combination with a plurality of oscillating cross-arms, of side-rails adapted to be reciprocated from the oscillation of said cross-arms, horizontally disposed cranks arranged between two of the cross-arms, a pitman connecting one crank to one end of one of the cross-arms, and a second pitman extending in the opposite direction and connecting the other crank to the opposite end of the other cross-arm.
7. In a tentering-machine, the combination with two horizontal cross-arms, pivot bearings for said cross-arms, side-rails mounted on the cross-arms on opposite sides of the pivots, a horizontal crank connected to one end of one of the cross-arms, a second crank connected to the opposite end of the other cross-arm, and means to rotate the cranks in the same direction to oscillate the cross-arms in unison.
8. In a tentering-machine, the combination with two pivoted cross-arms adapted to oscillate in a horizontal plane, side-rails supported on said arms, a pair of cranks adapted to rotate in a horizontal plane and having wrist-pins set on opposite centers, and pitmen connecting one crank with the end of one cross-arm and the other crank with the opposite end of the other cross-arm.

In testimony whereof I affix my signature in presence of two witnesses.

JOHN J. HOEY.
